US0D1095661S

(12) **United States Design Patent** (10) **Patent No.:** **US D1,095,661 S**
(45) **Date of Patent:** **** Sep. 30, 2025**

(54) **SYNTHESIZER**

- (71) Applicant: **Sequential Synths Limited**, High Wycombe (GB)
- (72) Inventors: **Stephen B. Starkweather**, Berkeley, CA (US); **Carson Day**, San Francisco, CA (US); **Andrew McGowan**, Half Moon Bay, CA (US)
- (73) Assignee: **Sequential Synths Limited**, High Wycombe (GB)

(**) Term: **15 Years**

(21) Appl. No.: **29/930,894**

(22) Filed: **Mar. 4, 2024**

(51) LOC (15) Cl. **17-99**

(52) U.S. Cl.

USPC **D17/99; D17/1**

(57) **CLAIM**

The ornamental design for a synthesizer as shown and described.

DESCRIPTION

FIG. 1 is a front top perspective view of the synthesizer;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a rear bottom perspective view thereof.

The broken lines shown in the drawings are for the purpose of illustrating portions of the article that form no part of the claimed design.

1 Claim, 4 Drawing Sheets
